(57) **CLAIM**

The ornamental design for a sliding lock, as shown and described.

DESCRIPTION

FIG. 1 is a front perspective view of a sliding lock showing our new design, the sliding lock being shown with its latch in a retracted position.

FIG. 2 is a rear perspective view thereof.

FIG. 3 is a front view thereof.

FIG. 4 is a rear view thereof.

FIG. 5 is a bottom plan view thereof.

FIG. 6 is a top plan view thereof.

FIG. 7 is a right side view thereof.

FIG. 8 is a left side view thereof; and,

FIG. 9 is another front perspective view thereof, the sliding lock being shown now with its latch in an extended position.
